FLOOR LAMP OR SIMILAR ARTICLE

Earl L. Canfield, Book Hill Road, Essex, Conn.

Filed June 15, 1964, Ser. No. 80,394

Term of patent 14 years

(Cl. D48—20)

FIG. 1 is a side elevation of a floor lamp showing my new design;

FIG. 2 is a top plan view thereof;

FIG. 3 is a cross-sectional view taken on line 3—3 of FIG. 1.

I claim:

The ornamental design for a floor lamp or similar article as shown.
